UNITED STATES PATENT OFFICE.

GEORGE A. BOWMAN, OF ST. LOUIS, MISSOURI.

SHIRT STUD OR BUTTON.

SPECIFICATION forming part of Letters Patent No. 393,416, dated November 27, 1888.

Application filed July 14, 1888. Serial No. 279,966. (No model.)

To all whom it may concern:

Be it known that I, GEORGE A. BOWMAN, a citizen of the United States, residing at the city of St. Louis, State of Missouri, have invented a certain new and useful Improvement in Shirt Studs or Buttons, of which the following is a full, clear, and exact description.

My invention relates to an improvement in shirt and collar studs or buttons, and has for its object to prevent the stiffness and irritation caused by the frictional contact of the ordinary shirt and collar studs with the neck and other parts of the wearer's body, this irritation sometimes, when the studs are made of inferior metals, producing abrasion of the skin and blood-poisoning.

My invention consists in a stud or button having a flexible base or back of india-rubber or other suitable material where it comes in contact with the skin, in lieu of the ordinary hard and rigid back.

On the accompanying drawings, Figure 1 represents a front view of my improved shirt and collar stud or button; Fig. 2, a central transverse section through the base or back of the stud, combined with the shank and head, seen in elevation; Fig. 3, an end view of the shank detached from the back of the stud; and Fig. 4 an end view of the back partly broken away, showing the end of the shank embedded therein, like letters of reference denoting like parts in all the figures.

The head *a* and shank *b* of my improved shirt and collar stud are composed of metal, 35 ivory, or other material, as with ordinary shirt studs. The lower end of the shank *b* is inserted centrally within the base or back *c*, which is preferably in the form of a circular or other shaped disk, composed of india-rubber, 40 leather, canvas, or some other flexible anti-corrosive material, and is concave or cup-shaped on its rear side, as shown. For securing the shank *b* to the back *c*, its lower end may be formed with flaring fangs or ears *d*, of 45 a curved shape, as shown in Figs. 1, 2, 3, or of a cruciform shape, as seen in Fig. 4; or these fangs or ears *d* may be of any other configuration as found most suitable for embedding and holding within the material of the back *c*, 50 which envelops the entire lower portion of

the shank *b* and extends along the latter either to the under side of the head *a*, as shown, or to any suitable distance therefrom. By this arrangement the back *c* of the stud, which presents a soft and flexible surface beyond the 55 shank *b*, (so sensitive to the movements of the wearer's body as to yield and give way even independently of the movement of the shank and head,) presses lightly on the skin, and by yielding to the movements of the neck 60 or other part of the wearer's body a feeling of comfort is imparted without any irritation or abrasion of the skin, as so frequently experienced with the studs or buttons in present use. 65

I am aware that shirt-studs have been constructed with elastic heads, which can be contracted to allow the button-hole to pass over and around them and then expand to secure the button-hole in its fastened position. I am also 70 aware that it has been proposed to provide a stud with two elastic heads for the same purpose; but I am not aware that a stud has ever been provided with a concaved or cup-shaped yielding flexible base adapted to relieve the 75 wearer of the pressure of the shank.

Therefore, I claim as my invention—

1. A shirt stud or button having a head, a shank, and a concave or cup-shaped base of yielding flexible material adapted to relieve 80 the wearer of the pressure of the shank, substantially as and for the purposes described.

2. In a shirt stud or button, the combination, with a rigid shank and head, of a concave or cup shaped yielding flexible base, substantially as and for the purposes described. 85

3. In a shirt stud or button, the combination, with a head and a rigid shank having a slotted flaring base, of an enlarged concave or cup-shaped yielding flexible base secured to 90 said shank, substantially as and for the purposes described.

In testimony whereof I affix my signature, in presence of two witnesses, this 7th day of July, 1888.

GEORGE A. BOWMAN.

Witnesses:

S. P. SCHRADER,
PAUL BAKEWELL.
